TERMINAL ARRANGEMENT FOR ROCKET
MISSILES

Nils-Erik Gustaf Küller, Karlskoga, and Karl-John Thorild Thorildsson, Bofors, Sweden, assignors to Aktiebolaget Bofors, Bofors, Sweden, a Swedish corporation

Application May 15, 1953, Serial No. 355,242

8 Claims. (Cl. 102—49)

The present invention relates to missiles in the form of rockets, particularly to rockets in which the firing charge is disposed between the rocket or war head containing the explosive charge and the propulsion charge and in which an electric detonating device for setting off the firing charge is actuated by connecting the detonating device by an electric cable with a distant power supply, that is a power supply separated from the rocket.

With rockets of the general type above referred to, the cable is usually guided through the rocket motor and led out through a nozzle at the rear end of the rocket motor. Experience shows that when the rocket is fired the cable is expelled with such force that it may injure personnel or pierce and otherwise damage an aircraft carrying the rocket.

Accordingly, the principal object of the present invention is to provide a novel and improved arrangement of the electric terminal connections for connecting the detonating device with the power supply by which the aforementioned disadvantages of the conventional arrangement are completely avoided.

Another object of the invention is to provide a novel and improved arrangement in which the terminal connections are so located that they are protected against the blast from the nozzle thereby preventing the aforementioned dangerous expulsion of the connecting cable when the rocket is fired.

Still another object of the invention is to provide a terminal arrangement in which the wire connections are led out through the side wall of the rocket rather than through the nozzle.

A further object of the invention is to provide a self-contained unit including the firing charge, its electric detonating device and its terminals and to fit the said unit in the outer side wall of the rocket thereby protecting the unit against the effect of the blast from the nozzle.

Other and further objects, features, and advantages of the invention will be pointed out hereinafter and set forth in the appended claims forming part of the application.

In the accompanying drawing several now preferred embodiments of the invention are shown by way of illustration and not by way of limitation.

In the drawing:

Fig. 1 is a fragmentary side view of a rocket missile according to the invention.

Fig. 2 is a section taken on line 2—2 of Fig. 1 on an enlarged scale.

Fig. 3 is a further enlarged detail view of Fig. 2.

Fig. 4 is a sectional view of a modification of the part shown in Fig. 3.

Fig. 5 is a cross-section of the rocket motor showing an embodiment of the invention in form of a self-contained unit.

Fig. 6 is a fragmentary sectional view of another embodiment of the invention, and

Fig. 7 is a detail view of Fig. 6 on an enlarged scale.

2

Referring first to Figs. 1, 2 and 3 in detail, these figures show a rocket having a war head 1 joined to the forward end of a generally tubular rocket motor 2 by a generally cylindrical intermediate member 3 which is threaded into head 1 and motor 2 respectively. The rear part of the rocket motor and the nozzle or nozzles extending therefrom are omitted as they are not essential to the understanding of the invention. The firing charge 4 is disposed within the rocket motor and is set off by means of an electric detonating device 5. The arrangement of both the firing charge and the detonating device is conventional. The detonating device is connected by a cable 6 with a power supply (not shown).

The terminal means according to the invention for connecting wires 7 and 8 leading from the detonating device 5 with cable wires 9 and 10 leading to the power supply comprise two terminal bushings generally designated by 11 and 12. Each of these bushings is shown as comprising a generally conical or pyramidal metal body 13 facing outwardly and ending in a threaded portion 14 protruding from the outer side wall of the rocket motor. The two bushings are fitted in correspondingly tapered holes 15 and 16 in the wall of the rocket motor. To obtain a tight fit of the metal bodies in the motor wall, the metal bodies are shown as being coated with an insulating sealing material 17. The ends of wires 7, 9 and 8, 10 are secured to the respective ends of the metal bodies, preferably by fitting the wire ends in corresponding bores of the metal bodies as can best be seen in Fig. 3. The two terminals 11 and 12 may further be insulated from each other by an insulation disk 18 which also serves to improve the sealing between the terminals and the wall of the rocket motor. The bushings formed by the terminals 11 and 12 are forced into sealing engagement with the motor wall by tightening nuts 19 and 20 respectively. A washer 21 may be interposed between the nuts and the insulation plate 18.

As appears from the previous description, the mounting of the terminals in the outer side wall of the rocket motor effectively prevents the aforementioned dangerous expulsion of the connecting cable when the rocket is fired.

Fig. 4 shows a modification of the terminal bushings according to Figs. 1 and 3 in which the coated metal body 13 is replaced by a conical or pyramidal insulation body 22 provided with an axial bore 23. Wire 7 is extended through said bore and ends in a threaded lug 24 which serves to receive tightening nut 19 and the outer wire 9 or 10 of cable 6.

Fig. 5 shows a terminal arrangement which is basically similar to the terminal arrangements of Figs. 2 to 4 but distinguished from these arrangements in that the terminal arrangement of Fig. 5 constitutes a self-contained unit. For this purpose, the firing charge 4, the electric detonating device 5 and the terminal bushings are mounted within a cartridge-like casing 25 which is fitted with a tight fit in a corresponding opening in the outer side wall of the rocket motor and can be withdrawn therefrom as a complete unit. Casing 25 may be secured in the rocket wall by any suitable means such as a threaded portion 26 which is threaded into corresponding threads in the wall opening.

Figs. 6 and 7 show a terminal arrangement which is also similar in principle to the previously described arrangements but distinguished from these arrangements in that the terminal bushings are mounted in an intermediate member 30 joining the war head 1 with the rocket motor 2 similar to the member 3 of Fig. 2. Member 30 is hollow and of generally cylindrical shape. It is considerably longer than member 3 and divided by a transverse partition wall 31. The outer wall of member 30 is provided with an annular groove 32 situated in juxtaposition with partition wall 31. The cross-sectional

configuration of the groove can be clearly seen in Figs. 6 and 7. The base of the groove which is next adjacent to firing charge 4 is provided with two tapered holes 33 for the terminal bushings, one hole and one bushing being shown in Figs. 6 and 7. The bushing comprises an outwardly tapered metal body 34 which may be covered with an insulating sealing material 35. The wires 7 and 9 are again secured to the ends of metal body 34 as has been described in connection with the previous figures. A portion 36 of metal body 34 protruding into the groove is threaded and serves to receive a tightening nut 37. Groove 32 is preferably lined with insulation material 38, and a washer 39 may be interposed between nut 37 and insulation layer 38.

Tightening of nut 36 will draw the terminal fittings against the tapered wall of opening 33. The sealing between the terminal fittings and the adjacent wall will be further increased in this embodiment of the invention and also in the previously described embodiments when pressure is developed within the rocket motor.

The second terminal bushing is identical with the previously described one so that it is not essential to illustrate the second terminal.

It will be apparent from the previous description that the terminal fittings of Figs. 6 and 7 may also be designed similar to the terminal of Fig. 4, that is, an insulation body may be provided through which the connecting wires are extended. It will further be apparent that with the terminal arrangement of Figs. 6 and 7 and also with the arrangements according to the previously described figures several conductors may be led out through a single terminal fitting.

Groove 32 is covered by a ring sleeve 40 which is fitted in corresponding annular recesses in war head 1 and member 30 respectively so that the ring sleeve is substantially flush with the outer wall of member 30 and rocket motor 2.

Ring 40 mounts a support member 41 for suspending the rocket. This member is of generally cylindrical shape and has an annular groove 42 to form support flanges. Member 41 is provided with an axial bore, preferably lined with insulation material 43. This bore serves to lead out the wire connections.

While the invention has been described in detail with respect to certain now preferred examples and embodiments of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. In a rocket missile having a war head, a generally tubular rocket motor, a firing charge and an electric detonating device for said charge disposed within the rocket motor, a generally cylindrical intermediate member joining the war head with the rocket motor and formed with an annular groove, electric terminal means extending through the wall portion of said member defining said groove for connecting the detonating device with a distant power supply, said terminal means comprising

outwardly tapered bushings having a portion protruding into said groove, and a sleeve member fitted upon said intermediate member for covering said groove flush with the outer side wall of the rocket motor.

5. A rocket missile according to claim 1, wherein a tightening means is fitted upon each of said bushings for tightening the same in the wall of said intermediate member.

10. A rocket missile according to claim 1, wherein a support means for suspending the rocket extends from the outside of said sleeve member.

15. A rocket missile according to claim 3, wherein the said support means are formed with bores therethrough for the passage of electric conductors leading to said bushings.

20. In a rocket missile having a war head, a generally tubular rocket motor, a firing charge and an electric detonating device for said charge disposed completely within the rocket motor housing and providing a substantially flat outer surface therewith, and electric terminal means extending in side by side parallel relationship through the outer side wall of the rocket motor housing and disposed directly behind said war head for connecting the detonating device with a distant power supply, said terminal means comprising conically tapered bushings with the bases thereof disposed within said housing, the narrow end of each of said bushings extending outwardly through said outer side wall of the rocket motor housing, said outer side wall having correspondingly tapered holes therethrough for sealing said bushings to said walls in response to pressure developed within the rocket motor, the effective seal of said bushing with said wall increasing in proportion to an increase in pressure developed within said motor.

25. A rocket missile according to claim 5, wherein each of said bushings comprises a solid tapered resilient insulation body having an axial bore therethrough for passage of an electric conductor of the terminal means, the wide end of each of said bushings extending into said motor and presenting a continuous convex surface.

30. A rocket missile according to claim 5, wherein each of said bushings comprises a tapered metal body, the side wall of said body being completely coated with a layer of resilient insulation material, said metal body constituting an electric conductor of the terminal means.

35. A rocket missile according to claim 5, wherein the narrow ends of said bushings are radially extended beyond the peripheral outline of the rocket motor, and wherein tightening means are fitted upon the protruding narrow bushing portions for tightening the bushings in their holes to provide a sealing engagement of said bushings with said motor wall.
